COMBINATION PUMP HOUSING AND MOUNTING MEANS

William H. Hamilton, Chicago, Ill., assignor, by mesne assignments, to Motor Products Corporation, Detroit, Mich., a corporation of New York

Filed Dec. 3, 1957, Ser. No. 700,358

2 Claims. (Cl. 103—219)

This invention relates to a combination pump housing and installation and particularly to a combination pump housing and mounting means for a "deep-well" installation or system.

A "deep-well" installation referred to herein is of the type wherein the source of liquid, usually water, to be pumped is too deep in the ground for a standard, or shallow well type, pump to raise it to the surface of the ground and wherein a portion of the liquid pumped by the pump is returned under pressure as "drive liquid" to a venturi device disposed in the well casing at approximately the depth from which a standard pump can raise the liquid to the surface of the ground. The venturi device provides a jet action to raise the liquid from its source to a position from which the pump may raise the liquid to the ground level where it may be delivered to a storage tank or system.

In some "deep-well" installations, it has been the practice to provide a pump, supporting means therefor, a suction pipe having a venturi device disposed therein at the proper depth, a liquid return pipe extending alongside the suction pipe to deliver "drive liquid" to the venturi device, and a series of connectors, elbows, fittings, etc., to properly connect the two pipes to each other and to spaced openings in the pump housing. Such an installation is relatively difficult and time consuming to install and requires a large number of parts. Some improvement has been made in such installations by arranging the suction pipe concentrically within a casing member with the "drive liquid" being delivered to the venturi device through an annular space defined between the suction pipe and the casing member. But even with such an improved installation, it is necessary to provide a series of joints, elbows, fittings, etc., for connecting the two pipes extending in side-by-side relationship from the independently supported pump respectively to the suction pipe and the annular space between the suction pipe and the casing at or above the ground level, thus still resulting in a relatively complicated and time consuming installation problem.

It is a general object of this invention to provide a new and improved combined pump housing and mounting means for a "deep-well" installation which overcomes the above disadvantages and provides a smooth, even pumping operation.

One of the objects of the invention is to provide a new and improved combination pump housing and mounting means for a pumping system having a concentrically arranged suction pipe and casing which requires a minimum of fittings, eliminates separate supporting means for the pump and motor, is very simple to install, and which therefore is both economical to produce and install.

A more detailed object of the invention is to provide such a combination pump housing and mounting means wherein the pump and motor are supported directly on the upper end of the well casing with the pump discharge chamber being in direct communication with the annular space between the concentric suction pipe and cas-

2

ing to direct a portion of the pumped liquid to the venturi device and with the upper end of the concentric inner suction pipe passing upwardly through the pump discharge chamber into direct communication with the pump impeller chamber to provide a liquid inlet thereto.

Certain other objects of the invention will, in part, be obvious, and will in part appear hereinafter. For a more complete understanding of the nature and scope of the invention reference may now be had to the accompanying drawings wherein:

Fig. 1 is a side elevational view, partially in vertical section, of a deep-well pump installation utilizing a preferred embodiment of the invention;

Fig. 2 is an enlarged horizontal sectional view taken generally along line 2—2 of Fig. 1; and

Fig. 3 is a vertical sectional detail view taken generally along line 3—3 of Fig. 2.

The pumping system shown in Fig. 1 includes a casing member 10 and an inner, smaller suction pipe 12 disposed concentrically therein so as to provide an annular space 14 between the outer surface of the suction pipe 12 and the inner surface of the casing 10. The casing 10 is driven into the ground into communication with a well or source of liquid to be pumped and the suction pipe 12 is inserted therein. A venturi device 16 of known type associated with the suction pipe 12 is adapted to be disposed at a depth from which liquid may be pumped to the ground level. The suction pipe 12 is also provided with double cup leathers 18 disposed below the venturi device 16 to provide a seal between the suction pipe 12 and the casing 10 so as to prevent the "drive liquid" from escaping downwardly into the well. A strainer 20 disposed at the lower end of the suction pipe 12 acts to strain impurities from the liquid pumped from the well.

A combination pump housing and mounting means, generally indicated by a reference numeral 22, includes a generally cylindrical housing 24 closed at the top by a fitting 25 and having a generally horizontal wall or baffle 26 formed therein adapted to divide the housing 24 into an upper pump impeller chamber 28 and a lower pump discharge chamber 30, the horizontal wall 26 acting as the lower wall of the pump impeller chamber 28 and as the upper wall of the pump discharge chamber 30. The two chambers 28 and 30 are suitably interconnected by fluid passages 31. A pump motor located within a housing 32 is adapted to be supported on top of the housing 24. The upper fitting 25 of the pump housing 24 tapers upwardly and inwardly to define an opening 34 through which passes a drive shaft 36 of the pump motor which is operably connected or coupled to a rotatable pump impeller 38 of known design disposed in the pump impeller chamber 28. A sealing member 39 is provided between the drive shaft 36 and the opening 34 in the fitting 25.

The lower integral portion 40 of the housing 24 is conically shaped and tapers downwardly and inwardly terminating in a depending neck portion 42 having a vertically extending bore 44 formed therein. The generally horizontal wall 26 is provided with a depending neck portion or circumferential flange 46 having an internally threaded bore 48 formed therein which is coaxial with and smaller in diameter than the bore 44 formed in the depending neck portion 42. The internally threaded bore 48 is adapted to receive in fluid-tight relation the upper externally threaded end of the suction pipe 12, as best shown in Fig. 3, so as to provide an inlet into the pump impeller chamber 28.

Referring particularly to Fig. 3, a pair of annular stepped grooves or counterbores 50 and 52 are formed on the inner surface of the lower end of the bore 44 in the depending neck portion 42 of the housing 24. The

upper annular groove 50 is smaller in diameter than the annular groove 52 and defines an annular shoulder 54 adapted to fit over and rest on the upper end of the well casing 10 to support the combination pump housing and mounting means 22 thereon. The suction pipe 12 extends in spaced relation upwardly through the bore 44 in the depending neck portion 42 so that the pump discharge chamber 30 is directly in communication with the annular space 14 formed between the suction pipe 12 and the casing 10.

In order to provide a liquid-tight seal between the casing 10 and the depending neck portion 42 of the housing 24, a sealing gasket 56 is disposed in the larger annular groove 52. An annular collar member 58 disposed about the casing 10 has an inner annular groove 60 formed in its upper end adapted to receive a portion of the annular sealing gasket 56. A series of vertically extending holes 62 are formed in the collar member 58 in alignment with a series of tapped holes 64 formed in the depending neck portion 42 of the housing 24. Bolts 66 extend through the holes 62 in the collar member 58 and into the holes 64 in the depending neck portion 42 so as to draw up the collar member 58 toward the depending neck portion 42 of the housing 24 and thus maintain the annular sealing gasket 56 in sealing engagement between the casing 10 and the depending neck portion 42 of the housing 24.

A discharge pipe 68 is threaded into a port 69 in the side of the housing 24 opening into the pump discharge chamber 30 to deliver pumped fluid through a pressure operated check valve 70, having a pressure gauge 72, and then through a pipe or conduit 74 to a suitable storage tank or distribution system (not shown). The usual conduit or tubing 76 is connected between the pump inlet and an air volume control associated with the storage tank. The pump end of the conduit 76 is connected to a port 78 formed in the depending neck portion 46 of the horizontally extending wall 26. A vent tube 80 is also provided leading to the valve 70 from the pump impeller chamber 28 to prevent an air lock in the system.

Installation of this pumping system is very simple and may be accomplished in a matter of a few minutes after the casing 10 is in place. The collar member 58 and the sealing gasket 56 are slipped over the casing 10 whereupon the suction pipe 12 is inserted in the casing 10 and the upper end is tightly screwed into the threaded bore 48 in the depending neck portion 46 of the horizontally extending wall 26. The pump housing 22 is then lowered until the shoulder 54 rests on the upper end of the casing 10 whereupon the bolts 66 are tightened into the holes 64 to draw up the collar member 58 toward the depending neck portion 42 of the housing 24 and compress the gasket 56 into liquid-tight sealing engagement. It is then a simple matter to connect the pipe 74 to a storage tank or distribution system and to properly connect up the tubings 76 and 80.

In operation, after priming and energizing the motor to rotate the impeller 38, liquid is drawn upwardly through the suction pipe 12 and into the pump impeller chamber 28 from which it is pumped as a result of rotation of the impeller 38 through the fluid passages 31 into the pump discharge chamber 30. The valve 70 will not open until the pressure in the pump discharge chamber 30 has been built up to the pressure (e.g. 25 lb./sq.in.) for which the valve 70 has been set. Therefore until this pressure has been built up in the pump discharge chamber 30, all of the liquid pumped into the chamber 30 is forced downwardly through the annular space 14 to the venturi device 16, this liquid being known as "drive liquid." The jet action of the fluid pumped through the venturi device 16 acts in the usual well known manner to raise liquid from the liquid source to a position in the suction pipe 12 wherein it may be raised by the action of the pump impeller 38 to the ground surface and pumped into the pump discharge chamber 30. After the pressure has been built up sufficiently in the pump chamber 30, the valve 70 will

open and a portion of the fluid pumped will be delivered to the storage tank or distribution system with the remainder of the fluid pumped passing downwardly through the annular space 14 to provide "drive liquid" for the venturi device 16.

It will be understood that certain changes may be made in the construction or arrangement of the combination pump housing and mounting means disclosed herein without departing from the spirit and scope of the invention as defined in the appended claims.

I claim:

1. A combination pump housing and mounting means for wholly supporting a pump on the upper projecting end of an upright well casing and for supporting a substantially smaller suction pipe concentrically within said casing, said pump housing comprising, an upper cylindrical portion, a lower inverted conical portion depending concentrically therefrom with the largest diameter of said conical portion being substantially equal to the diameter of said upper cylindrical portion, a baffle enclosing the top of said cylindrical portion, said baffle having an impeller chamber in the central portion and there being an internally threaded circumferential flange depending from the center of said impeller chamber down into said inverted conical portion and terminating in spaced relation therein, a depending neck portion on the bottom of said conical portion being in approximately concentric alignment with said circumferential flange, said neck portion having a double counterbore so as to provide an inner annular shoulder and an outer annular shoulder, said inner annular shoulder being adapted to fit over the upper end of said upright well casing for wholly supporting said pump housing thereon, the inner suction pipe adapted to extend in spaced relation through said neck portion and through said inverted conical portion with its upper end adapted to be secured in said internally threaded circumferential flange to provide a fluid inlet to said impeller chamber from which chamber fluid may be pumped into said inverted conical portion through passages formed in said baffle, a portion of said pumped fluid adapted to pass downwardly from said inverted conical portion into an annular space defined between the well casing and the suction pipe, a sealing gasket disposed against the outer annular shoulder of said double counterbore of said neck portion, and a collar disposed on the well casing and adapted to be drawn up toward said neck portion to compress said gasket against said outer annular shoulder to provide a fluid-tight seal between said neck portion and the well casing.
2. A combination pump housing and mounting means for wholly supporting a pump on the upper projecting end of an upright well casing and for supporting a substantially smaller suction pipe concentrically within said casing, said pump housing comprising, an upper cylindrical portion, a lower inverted conical portion depending concentrically therefrom and terminating in a depending neck at the bottom of said conical portion having a vertically extending bore formed therein, a baffle enclosing the top of said cylindrical portion, said baffle having an impeller chamber in the central portion and there being an internally threaded circumferential flange depending from the center of said impeller chamber into said inverted conical portion and terminating in spaced relation therein, said internally threaded circumferential flange being substantially in coaxial alignment with said bore in said depending neck, fluid passage means extending between the impeller chamber and a pump discharge chamber defined by said baffle and said inverted conical portion, the suction pipe being adapted to extend in spaced relation through said bore and to have its upper end tightly secured in said internally threaded circumferential flange to provide a fluid inlet to the impeller chamber, means defining two stepped annular grooves formed in the lower end of said bore in said depending neck with the uppermost groove having the smaller diameter and defin-

ing an annular shoulder adapted to rest on the upper end of the upright well casing to wholly support the pump housing thereon, an annular sealing gasket adapted to be fitted in the other groove, and a collar fitted over the well casing and adapted to be drawn up toward the lower end of said depending neck to compress said gasket into fluid-tight sealing engagement between the well casing and a second annular shoulder defined by the other groove in said depending neck of the pump housing, said structure providing a path for a portion of the pumped fluid leading directly from said pump discharge chamber downwardly between the concentric suction pipe and well casing to a venturi device disposed in a lower portion of the well casing, the remainder of the pumped fluid adapted to be

delivered from said pump discharge chamber to a storage tank or distribution system through a pressure operated check valve.
